AUTOMATIC SWITCH FOR ULTRA HIGH FREQUENCY

Ernest C. Okress, Montclair, N. J., assignor to Westinghouse Electric Corporation, East Pittsburgh, Pa., a corporation of Pennsylvania

Application October 16, 1942, Serial No. 462,261

14 Claims. (Cl. 178—44)

1

This invention relates to electricity of ultra-high frequency, and more particularly, to an automatic switch for controlling the flow of such energy in a wave guide.

The principal object of my invention, generally considered, is an improved automatic ultra-high frequency switch of the type generally designated as a "TR" box, whereby such an instrument is adapted to be put together by welding certain parts.

Another object of my invention is to construct a "TR" box with an annularly corrugated flexible metal diaphragm wall carrying an electrode movable by means of an adjusting cap or drum head, to flex the diaphragm wall for tuning the cavity, and simultaneously vary the position of the electrode carried thereby with respect to an associated electrode on a fixed wall of said cavity.

Another object of my invention is to construct an automatic switch, of the type designated as a "TR" box, in such a manner that parts may be put together by welding, thereby substantially eliminating the use of glass and reducing the amount of solder used in its construction.

Other objects and advantages of the invention, relating to the particular arrangement and construction of the various parts, will become apparent as the description proceeds.

Referring to the drawing:

Fig. 1 is an axial vertical sectional view, after assembly and welding, of a wave guide and associated "TR" box embodying my invention.

Fig. 2 is a plan of the combined structure shown in Fig. 1.

Fig. 3 is a horizontal axial sectional view on the line III—III of Fig. 1, in the direction of the arrows.

Fig. 4 is a horizontal sectional view on the line IV—IV of Fig. 1, in the direction of the arrows.

Fig. 5 is an enlarged fragmentary view corresponding to a portion of Fig. 1, before the welding is effected.

Fig. 6 is a view corresponding to Fig. 5 but showing a modification.

Fig. 7 is an elevational view of the switch of my invention and mechanism normally associated therewith.

In the Okress et al. application, Serial No. 451,356, filed July 17, 1942, and owned by the assignee of the present application, there is described and claimed an automatic switch for controlling the flow of ultra-high frequency electricity in a wave guide to thereby protect associated apparatus. The automatic switch or "TR" box of said application comprises means for tun-

2

ing the box cavity and adjusting the spacing of spark gap electrodes. The maintenance of the box cavity in an evacuated condition includes the use of glass-to-metal seals.

5 In accordance with the present invention, the construction of such a switch or "TR" box is improved by the substantial elimination of glass-to-metal seals and the employment instead of welded connections, such connections being sufficiently removed and electrically isolated from the action of the transmitted high frequency energy that deleterious effects are not produced.

10 A "TR" box is, in principle, a modified coaxial resonant cavity having a discontinuity in its central conductor produced by a gap. Provision is made for adjusting the gap length and tuning the cavity.

15 Referring now specifically to the drawing, and first considering the diagrammatic showing in Fig. 7, the reference character 11 designates a wave generator for producing energy of a desired ultra-high frequency which is transmitted along a metal wave guide 12, which in the present embodiment is of hollow rectangular cross section, 20 to an antenna 13, which is shown as a parabolic device for directing a beam in a desired direction toward an object. The invention is to be used with ultra-high frequency radio waves which may be projected and reflected in substantially the same manner as light waves.

25 Accordingly the projected wave energy may be directed toward some object, reflected therefrom, and on its return course intercepted by the same antenna which concentrates and causes it to re-enter the guide 12 and travel therein and through a branch tube 14 to excite a receiver 15. Obviously the returning wave energy will be very weak compared to the transmitted energy and a "TR" box 16 is, therefore, interposed in the branch tube 14 to check the flow of any high-powered energy and yet permit the receiver to be actuated by the relatively weak energy of a returning signal.

30 The switch or "TR" box of the present invention comprises a cylindrical body 17 of conductive material, preferably metal such as "Kovar," which may be welded. The body 17 intersects the conductive, preferably metal wave guide branch 14, as shown most clearly in Figs. 1 to 5, inclusive, and is united thereto, as by means of solder 18. This cylindrical member also carries quarter wavelength conductive cylindrical, preferably metal, sections 19 and 21, each having inner outstanding annular portions 22 and 23 35 united to the inner surface of the cylindrical

member 17, or formed integral therewith. The mode of connection may be soldering if not formed integral. This means that the cylindrical member 17 carries a pair of coaxial cylindrical portions, the free edges of which extend outwardly away from one another and the inner edges of which are connected to said cylindrical portion in line with the upper and lower walls of the wave guide 14, as shown most clearly in Fig. 1.

The cylindrical portion 17 also carries windows 24 and 25 of suitable dielectric material such as "No-loss" glass which serves to pass the micro-wave energy in the guide 14 through the "TR" box 16. Said windows are suitably dimensioned, both as to diameter and thickness and with due consideration to their dielectric constant, to introduce a minimum of disturbance and still give sufficient coupling between the "TR" box cavity and the wave guide. These windows are shown convex outwardly in order to better withstand the outside pressure when the box cavity is evacuated, desirably generally circular, and disposed with their centers on the axis of the wave guide 14. They are desirably as small as practicable for obtaining the desired energy transfer without undue lessening of the surface continuity of the resonator volume of the box. These windows are made vacuum tight as by sealing in place in the cylindrical member 17.

In the present embodiment, tuning of the resonator chamber of the "TR" box 16 is effected by making the upper wall of said chamber 26 as a flexible conductive or metal diaphragm 27, desirably provided with concentric annular corrugations, as shown most clearly in Figs. 1 and 4. To the central portion of the diaphragm 27 is secured an adjustable electrode 28 provided with a threaded stem 29 outstanding therefrom, and carried by the hub portion 31 of an adjusting drum or nut member 32 threadably engaging the cylindrical member 17, as indicated at 33. The threads on the electrode extension and cylindrical member 17, if both right handed, for example, are necessarily of different pitch in order to provide for adjustment of the electrode 28 and diaphragm 27 by turning the head 32, the peripheral portion of which is desirably knurled, as indicated at 34. From a practical standpoint it is preferable to have the pitch of the threads on the extension 29 greater than that of the threads 33.

The bottom wall 35 of the resonant cavity 26 is desirably rigid and carries a hollow electrode 36, the lower portion of which may be closed by a block of material 37, such as glass, carrying a probe 38 one end of which is impregnated with a salt of radium or other radio-active material 39, for inducing the generation of photo-electrons to decrease the breakdown potential between the electrodes 28 and 36. Other "keep-alive" means may be substituted for the radioactive probe.

The flexible wall 27 and the relatively rigid wall 35 are carried by hollow cylindrical members 41 and 42, of "Kovar" or other weldable conductive material, provided with outstanding annular flanges 43 and 44 respectively welded to the outer edge portions of the cylindrical member 17, as indicated at 45 and 46. The outstanding flanges 43 and 44 may initially have annular corrugations or bosses 57 extending toward the adjacent edges of the cylindrical member 17 to facilitate the formation of welds there-

between, as illustrated in Fig. 5. By virtue of having these welds disposed at a relatively great distance from the wave guide 14 and with what amount to filters or "choke plates" therebetween, there is no danger of any undesired action, such as spark over, adjacent the joints, as might be the case if said joints were disposed close to or not electrically isolated from, the resonant cavity defined by the cylindrical member 17 and the portions 27 and 35.

The sections 19 and 21 both have lengths corresponding to a quarter wave whereby a high impedance is induced at the openings 47 and 48, as the impedance of the spaces 49 and 50 is equal to

$$\frac{4}{\pi} Q Z_0$$

where Q is the merit factor of said spaces and Z_0 the characteristic impedance, which is high because Q is high. This high impedance at 47 and 48 is transformed, through the characteristic impedance of the spaces 51 and 52, to a very low impedance at the annular gaps 53 and 54, causing the same to act electrically shorted although mechanically no metallic contact exists. The Q of the resonant cavity 26 is somewhat reduced by this construction, but not seriously.

After connecting the cylindrical portion 17 with the associated cylindrical portions 19 and 21 to the wave guide 14, and welding the flanges 43 and 44 to the cylindrical portion 17, to assemble the wall portions 27 and 35 and their associated electrodes therewith, the adjusting drum or nut 34 may be applied in any desired manner, as by turning in place on the ends of the associated threads respectively carried by the cylindrical portion 17 and the electrode extension 29, starting with the electrodes 28 and 36 either touching or very close together so that upon turning on the adjusting drum said electrodes are gradually separated until in the position illustrated in Fig. 1 where they are in approximately the correct adjustment, with the flexible wall 27 disposed substantially parallel to the fixed wall 35.

As an alternative the drum may be formed in two parts adjustably connected as by screws 55 after the parts have been individually turned in place on the cooperating threads 33 and 29. This latter construction avoids the necessity of initially flexing the diaphragm 27.

Any desired means may be provided for evacuating the chamber 26, such as an exhaust tube 56 extending from the glass block 37.

Referring now to the embodiment of my invention illustrated in Fig. 6, the cylindrical member 17^a is there shown with an outstanding peripheral annular flange 58, and the cylindrical member 42^a is likewise provided with an annular flange 44^a corrugated as indicated at 57^a for uniting with the flange 58 as an alternative to the welded connection 46 of the first embodiment. A similar welded construction may be substituted for the welds 45 of the first embodiment.

From the foregoing disclosure, it will be seen that I have provided for the use of welds to hasten and cheapen the manufacture of "TR" boxes. Such welds are separated from the resonant box cavity by parts of sufficient impedance, so that the welded joints are isolated and prevented from interfering with the resonant characteristics.

In operation, when high power tends to pass down the wave guide 14 toward the receiver 15,

the potential difference developed between the electrodes 28 and 36, after proper tuning of the cavity 26 and adjustment between the electrodes, the breakdown potential therebetween being lowered by the "keep alive" probe 38, is sufficient to cause sparking between said electrodes, resulting in a large impedance mismatch which acts as an excellent reflector of energy attempting to get through to sensitive receiving apparatus 15. When, however, a signal is being received, the 10 energy thereof is so weak that no breakdown occurs and said energy is transmitted to the receiver as desired.

Although preferred embodiments of my invention have been disclosed, it will be understood 15 that modifications may be made within the spirit and scope of the appended claims.

I claim:

1. In combination, an elongated hollow conductive structure adapted to function as a guide 20 for electricity of ultra-high frequency, a resonator comprising a hollow outer metal member intersecting said guide structure, hollow inner metal members having inner electrode-carrying closure portions cooperating with said outer metal member to define a resonant cavity and terminating in flanges extending outwardly and welded to said metal member, and filter means disposed between said outer and inner members and extending from the guide structure toward the welds 30 for electrically isolating the latter from said resonator cavity.

2. In combination, an elongated hollow conductive structure adapted to function as a guide for electricity of ultra-high frequency, and a resonator comprising a hollow outer metal member intersecting said guide structure and enclosing coaxial spark-gap electrodes, each electrode being carried by a wall of said resonator, each wall being bordered by portions extending outwardly from its periphery and terminating in a flange overlying and welded to an end portion of said outer metal member.

3. In combination with an elongated hollow conductive structure adapted to function as a 45 guide for electricity of ultra-high frequency, a resonator comprising a hollow outer metal member intersecting said guide structure and enclosing coaxial spark-gap electrodes, each electrode being carried by a wall of said resonator, each wall being bordered by portions extending outwardly from its periphery and terminating in an outwardly extending flange welded to an end portion of said outer metal member, and means for tuning said resonator and adjusting the distance 50 between said electrodes.

4. In combination with an elongated hollow conductive structure adapted to function as a guide for electricity of ultra-high frequency, a resonator comprising a hollow outer metal member intersecting said guide structure and enclosing coaxial spark-gap electrodes, a flexible diaphragm carrying one of said electrodes, a fixed wall portion carrying the other of said electrodes, and hollow metal portions extending away from one another and the peripheries of said diaphragm and fixed wall portions and each terminating in an outwardly extending flange welded to end portions of said outer metal member.

5. In combination with an elongated hollow conductive structure adapted to function as a guide for electricity of ultra-high frequency, a resonator comprising a hollow outer metal member intersecting said guide structure and enclosing coaxial spark-gap electrodes, each electrode 70

being carried by a wall of said resonator, each wall being bordered by portions extending outwardly from its periphery and terminating in a flange overlying and welded to an end portion of said outer metal member, one of said electrodes being hollow, and a probe disposed coaxially within said electrode and insulated therefrom, and means associated with said probe for lowering the breakdown potential between said electrodes.

6. In combination with an elongated hollow conductive structure adapted to function as a guide for electricity of ultra-high frequency, means intersecting said guide structure and defining therewith a resonator chamber enclosing coaxial spark-gap electrodes, each electrode being carried by a wall of said resonator coplanar with a wall of said guide exterior of said chamber, and means providing for exhausting said resonator chamber and making it vacuumtight.

7. In combination with an elongated hollow conductive structure adapted to function as a guide for electricity of ultra-high frequency, means intersecting said guide structure and defining a resonator chamber enclosing coaxial spark-gap electrodes, each electrode being carried by a wall of said resonator, one of said electrodes being hollow, and means communicating with the interior of said hollow electrode for exhausting said resonator chamber.

8. In combination with an elongated hollow conductive structure adapted to function as a guide for electricity of ultra-high frequency, a resonator comprising a hollow outer metal member intersecting said guide structure and enclosing coaxial spark-gap electrodes, each electrode being carried by a wall of said resonator, each wall being bordered by portions extending outwardly from its periphery and terminating in a flange overlying and welded to an end portion of said outer metal member, and filter means disposed between the cavity of said resonator and said welds for isolating the latter and preventing them from interfering with the characteristics of the former.

9. In combination with an elongated hollow conductive structure adapted to function as a guide for electricity of ultra-high frequency, a resonator comprising a hollow generally cylindrical outer metal member intersecting said guide structure and enclosing coaxial spark-gap electrodes, means associated with one of said electrodes for lowering the breakdown potential, a flexible diaphragm carrying one of said electrodes, a fixed wall portion carrying the other of said electrodes, hollow cylindrical portions extending outwardly from the periphery of said diaphragm and fixed wall portions, each terminating in an annular flange extending outwardly and welded to an outer portion of said outer metal member, filter plates disposed between said guide structure and welds for isolating the latter from the resonant cavity defined by the guide structure and cylindrical portion, and means for tuning said resonator and adjusting the distance between said electrodes comprising a drum head threadably mounted on said outer metal portion and threadably receiving an extension of the electrode carried by said flexible metal member, the threaded portions on the cylindrical member and electrode extensions differing in pitch whereby turning of said drum head adjusts the position of the flexible metal wall portion and electrode carried thereby with respect to the other electrode.

10. A "TR" box comprising a hollow body res-

onator with a cavity defined by portions of the walls of a hollow conductive structure adapted to function as a guide for electricity of ultra-high frequency and a hollow outer metal member intersecting said guide structure, with lateral extensions from walls of said guide structure welded to end portions of said outer metal member at points remote from the resonator cavity.

11. In combination with an elongated hollow conductive structure adapted to function as a guide for electricity of ultra-high frequency, a "TR" box intersecting said guide structure and comprising a hollow body resonator, opposed spark-gap electrodes enclosed thereby, and means for flexing a wall of said resonator which is generally coplanar with a wall of said guide to simultaneously tune the same and adjust the gap between said electrodes.

12. A "TR" box comprising a hollow body resonator, opposed spark-gap electrodes enclosed thereby, means for flexing a wall of said resonator to simultaneously tune the same and adjust the gap between said electrodes, and means associated with one of said electrodes for lowering the breakdown potential therebetween.

13. A "TR" box comprising a hollow body resonator, opposed spark-gap electrodes enclosed thereby, means associated with one of said electrodes for exhausting the resonator cavity, and means for flexing a wall of said resonator to simultaneously tune the same and adjust the gap between said electrodes.

14. A "TR" box comprising a hollow body resonator, opposed spark-gap electrodes enclosed thereby, means for flexing a wall of said resonator to simultaneously tune the same and adjust the gap between said electrodes, welds connecting the resonator body to an associated wave guide, and means for electrically isolating said welds from said wave guide to eliminate their influence on the characteristics of the resonator cavity.
